ATTORNEY

UNITED STATES PATENT OFFICE.

NEIL A. STRAND, OF BROOKLYN, NEW YORK.

SAFETY RAZOR.

Application filed February 4, 1926. Serial No. 85,817.

This invention relates to cutlery and has particular reference to safety razors.

Among the objects of the invention is to provide a safety razor having a flexible blade provided with a plurality of cutting edges, said edges being all substantially straight and constituting the entire periphery of the blade.

Another object of the invention is to provide a safety razor blade of normally flat form and of diamond or rhombus shape having four cutting edges of equal length each disposed at an oblique angle to the next around the entire periphery of the blade, the blade thus having two oppositely disposed acute angles and two oppositely disposed obtuse angles.

A still further object of the invention is to provide a safety razor including a guard and blade holding means co-operating therewith, the guard and holding means being similarly formed, each having flat end portions disposed at an obtuse angle to each other and flaring outward or in a direction away from the handle and the bisector of the angle which is coincident with the axis of the handle.

A further object of the invention is to provide a safety razor having a blade with a plurality of cutting edges forming the complete periphery thereof, the periphery being divided into a plurality of cutting edges, the edges being selectively operative for shaving purposes in succession without adjustment of the holding means and handle, and so disposed with respect to the axis of the handle that the blade may be moved over the face in shaving along a path parallel to the handle and direction of movement of the handle while the cutting edge occupies an inclined position with respect to said axis and direction of movement.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which

like reference characters designate the same parts in the several views, and in which—

Figure 1 is a side elevation of a preferred embodiment of the invention in assembled condition.

Fig. 2 is a side elevation of the same mechanism in dispersed condition.

Fig. 3 is a bottom plan view of the top or holding plate.

Fig. 4 is a plan view of a blade.

Fig. 5 is a transverse sectional detail on the line 5—5 of Fig. 1.

Fig. 6 is a top plan view or as would be seen on looking down in Fig. 1, but with portions broken away, showing particularly the disposition of the guard fingers with respect to each other and the cutting edges of the blade.

Fig. 7 is a diagram indicating the manner of formation of the blades from a single uniform strip of steel.

Referring now more specifically to the drawings, I show my improved razor which comprises complete but four parts including the blade, said four parts being a guard plate 10, a top or holding plate 11, a blade 12, and a handle 13.

The handle is of any suitable design preferably straight and rounded so as to be formed rapidly and cheaply on a screw machine, and provided with a threaded socket 14 at one end.

The guard plate is of rigid material having two flat end portions disposed at an oblique angle to each other and having a central hole 15 adapted to register with the socket 14. In plan the plate 10 is in the form of a rhombus having four equal sides and having a series of guard fingers 16 formed along the edges, all the fingers being parallel to one another, while at the points or angles there are formed guard points 17 and 18. All the fingers and guard

points are bent downward slightly from the planes of the parts to which they are connected, or toward the handle, but serve to effectively guard the sharp cutting edges and the several angles or points of the blade, all of which are sharp. Transversely or

along the narrow dimensions of the guard plate, the plate is straight as shown clearly in Fig. 5. The flat end portions of the

guard plate at convenient points between the extreme ends and the central hole 15, are provided with holes 19.

The blades 12 are of equilateral quadrilateral form or diamond shape and are cheaply and rapidly formed from ribbon like metal such as steel as indicated in Fig. 7 by a succession of diagonal cuts 20. Either coincident with the cutting of the blades from the strip or at any other time, each blade is formed with a central hole 21 and two end holes 22 which are adapted in practice to register with the holes 19 in the guard plate. The four edges of each blade being straight are easily sharpened for cutting purpose, making a cutting edge around the entire periphery of the blade, and thereby the facility for re-sharpening the blades if desired is increased over blades having curved cutting edges. These blades are normally flat but being of thin metal are capable of easy flexing between their ends so as to adapt them to conform to the flat surfaces of the guard plate.

Any suitable means may be provided to flex the blade to make it conform to and be held in place against the guard plate for practice, this means being shown as comprising the top or holder plate 11, which like the guard plate is of rigid metal and shaped so that it possesses two flat end portions having the same angle of divergence from each other as the guard plate. Preferably the shape of the holding plate is similar to that of the blade and guard plate, though slightly smaller than the blade so as to expose the required amount of the cutting edge portion of the blade for shaving purposes. In the axial center of the top plate 11 is fixed a stud or screw 23 adapted to pass downward through the hole 21 in the blade, the hole 15 in the guard plate, and into the socket 14 of the handle. When the plates are brought into close relation with each other with the blade between them and the handle affixed to the screw and tightened, the blade will be adjusted in practical position for shaving purposes and the parts will all be held from relative movement. Means is provided also to prevent relative rotation of the plates and blade, this means being shown as a pair of pointed studs 24 fixed to the under side of the end portions of the top plate and extending downward with their axes substantially parallel to each other and preferably diamond shape in cross section to harmonize with the general configuration of the instrument and to possess relatively sharp points adapted to pass readily through the holes 22 in the blade and into the holes 19 of the guard plate. This taper of the studs insures easy assembly of the parts even though the blade is normally flat. It is to be understood, however, that with respect

to the shape of these studs or any other secondary details I do not wish to be unnecessarily limited.

To assemble the razor the blade is placed upon the center stud or screw 23 and the stud is then passed through the hole 15 of the guard plate, the operator applying force enough upon the plate to cause the stud 23 to be engaged in the socket 14 of the handle, and then by holding the plates and blade in one hand and turning the handle with the other hand, the parts are clamped together and the studs 24 are caused to pass through the registering holes 22 and 19. In the use of the razor the handle is grasped in any convenient manner and either of the side edges of the plate will be drawn over the face, the position of the cutting edge being inclined to the axis of the handle when the handle is drawn directly forward or downward parallel to or in line with its axis, as a result of the upward obliquity of the end portion of the blade bearing the active edge and also because of the triangular or tapered form of such end of the blade. While for easy access to those portions of the face not ordinarily easily accessible, as for the upper lip, any acute angular portion of the blade may be employed in advance of the broader portion, for usual normal shaving purposes the handle and razor will be drawn directly in line with the handle, the broader point or portion of the blade moving in advance of the narrower or sharper point thereof. In any event, however, all portions of the blade are amply guarded by the guard fingers and guard points to safeguard the shaver from being pricked or cut. Again, the parallel arrangement of the fingers 16, or with the arrangement of the fingers along one edge directly in line with those of that edge directly across the narrower end portion of the blade, is most favorable for the reception of the beard along or between the fingers while the razor is drawn in the line of the axis of the handle and with the shorter point of the blade trailing behind the broader point above described and making an inclined cut across the face.

I claim:

1. In a safety razor, the combination of a guard plate, a top plate, a blade between said plates, said plates being of obtuse angular formation lengthwise thereof, a handle, and means associated with the plates and co-operating with the handle to hold the plates in operative position, the end portions of the plates diverging from each other in a direction remote from the handle.

2. In a safety razor, the combination of a handle, a guard plate having two flat portions disposed at an angle to each other, the bisector of said angle being coincident with

the axis of the handle, the flat portions of the guard being divergent from each other in a direction away from the handle and said bisector, a normally flat blade, and means to flex the blade centrally to cause it to conform to and be held against the guard.

3. The combination as set forth in claim 2 in which the blade is formed with cutting edges along its entire periphery.

4. The combination as set forth in claim 2 in which the blade is provided with four cutting edges intersecting one another in oblique angles, the guard plate serving to cover and shield the angles of the blade as well as the cutting edges thereof.

5. In a safety razor, the combination of a guard plate and a clamping plate both having similar obtuse angle formations, a blade between said plates, adjustable means serving to bind the plates in close relation to each other with the blade gripped between them, and auxiliary means extending from one plate through the blade and to the other plate to prevent relative rotation between the blade and the plates, said auxiliary means including a stud projecting at an oblique angle from the plate which carries it and having its axis parallel to the axis of the binding means.

6. In a safety razor, the combination of a handle having a threaded socket at one end, a guard plate having an obtuse angular formation and located adjacent to said socket with the end portions of the plate diverging from each other and away from the handle, a blade adjacent to the guard plate, said plate and blade having registering central holes, a clamping plate adjacent to the blade and having a rigid screw projecting from its center through said registering holes and having adjustable co-operation with said socket, said blade and plates being of similar diamond shape, and a pair of rigid studs having parallel axes projecting from one of said plates toward the other, said other plate and blade having holes to receive said studs, said studs being tapered and of diamond shape in cross section.

In testimony whereof I affix my signature.

NEIL A. STRAND.
